MEANS FOR ACTUATING A WATER FLUSHING DEVICE

Application filed April 24, 1930, Serial No. 446,950, and in France April 26, 1929.

The present invention relates to means for automatically flushing the water in latrines and its object is to remedy the negligence of the users. The means cooperate with the opening of the door of the latrines and are of an electromagnetic nature.

The electromagnetic system according to this invention comprises an electromagnet whose movable armature is secured to the lever releasing the flush of water and which is switched on by means of a switch actuated by means of a door knob or the like used for opening the door. This device automatically actuates the flushing device when the user leaves the latrine, but is not brought into action when the user enters it.

The accompanying drawings show various embodiments of the invention by way of example, which are not of a limited nature.

Figures 1, 2, 3 and 4 show an electrical fastening device according to this invention. Figure 5 is a diagram showing the electrical connections. Figure 6 represents a device for opening a door. Figure 7 shows a door of the latrine together with means for operating the flushing device. In the drawings 1 is a staple, 2 is a lock bolt, 3 is an operating handle or knob, 4 is a stud rigidly secured to said bolt and 5 is a recess into which the lock bolt may enter, formed in an insulating disk 6 on which are mounted the terminals 7 and 8 connected to the circuit of an electromagnet. The terminal 8 carries a spring strip 9, whose outer end carries a contact piece 10. The terminal 7 carries a second spring strip 11 on whose outer end is disposed a plate 12 of an insulating substance, which carries on its face adjacent the contact piece 10 a second contact piece 13 connected electrically to the terminal 7 in any suitable manner, not shown in the drawings, and adapted to come into contact with said contact piece 10. The plate 12 carries, on its face next the recess 5, a ramp 14 adapted to come into contact with the stud 4 during the motion of the lock bolt in both directions. The several parts of the electric fastening device are mounted upon a metallic plate, not shown in the drawings, which is secured to the door adjacent the bolt 1.

The operation of the fastening device shown in Figures 1, 2, 3 and 4 is as follows:

Figure 1 shows the device in the closed position, and herein the stud 4 is at the exterior of the recess 5; the strip 11 is in the inoperative position; the contact pieces 10 and 13 are separated. Figure 2 shows the said device in its opening position. By means of the knob 3, the bolt 2 is moved in its guides in the known manner; the stud 4 enters the recess 5 and comes into contact with the upper part of the ramp 14, thus lowering the ramp and with it the plate 12 as well as the contact piece 13 which now meets the contact piece 10 and thus closes the circuit of the electromagnet.

Figure 3 shows the lock bolt in a completely opened position. The stud 4 is outside of the ramp 14, which is freed from its pressure and returns together with plate 12 to the inoperative position under the action of the spring strip 11; the contact pieces 13—10 are separated and the circuit of the electromagnet is again opened.

Figure 4 shows the lock bolt during its closing movement. When controlled by the knob 3, said bolt leaves its recess 5. The stud 4 comes into contact with the lower part of the ramp 14, so that the ramp will be raised together with the plate 12 and the contact piece 13, the circuit of the electromagnet remaining open; after the stud 4 has finally left the ramp (Fig. 1) the ramp is released and is brought, together with the plate 12 and contact piece 13, into the inoperative position, the circuit of the electromagnet being open.

Thus the whole operation of the lock bolt has only caused a momentary closing of the circuit of the flushing electromagnet when the door is opened for the exit from the latrines.

Figure 5 shows the electromagnetic arrangement; 15 and 16 are two electromagnets having a common armature 17, pivoted at 18, and adapted to come into contact with the contact piece 19 or 20. The armature can be pressed against either of the two contact pieces by means of a spring, not shown in the drawings. The switch device 21 comprises a door contact, the circuit being closed when

the door is opened, or inversely. The contact device 22 represents a switch disposed within the staple of the lock bolt, in such manner, that the circuit will be closed when the door is fastened and the lock bolt is entirely inserted into the staple, this contact ceasing when the lock bolt is removed from the staple.

The contact device 23 comprises a switch controlled by an arm 24 mounted upon the armature 25 of the electromagnet 26, which, when energized, sets off the flush of water. The electric contact is closed by the switch 23 when the electromagnet 26 is energized and its armature 25 is entirely withdrawn into the electromagnet 26. The contact is opened when the electromagnet is no longer energized and the armature 25 and the arm 24 resume the inoperative position as shown in the drawings.

These parts form three circuits which are supplied with current by means of terminals 27 and 28. The first circuit comprises the terminal 27, the pivot 18, the armature 17 in its position represented by the full lines, the terminal 19, the electromagnet 16, the contact 22 and the terminal 28. The second circuit comprises the terminal 27, the pivot 18, the armature 17 in its position represented by dotted lines, the terminal 20, the contact piece 21, the flushing electrode 26 and the terminal 28. The third circuit comprises the terminal 27, the electromagnet 15, the contact piece 23 and the terminal 28.

In Figure 5 the diagram shows the position of the parts before a person enters the latrines. When he enters, he closes the fastening device, thereby making a contact at 22. The current passes through the terminal 27, the pivot 18, the armature 17, the terminal 19, the electromagnet 16, the contact piece 22, the terminal 28; thus the electromagnet 16 is energized and the armature 17 takes the position shown by dotted lines against the contact piece 20.

When the person leaves, the door contact is made at 21, and the current passes through the terminal 27, the pivot 18, the armature 17, the terminal 20, the contact 21 and the flushing electromagnet will thus be energized and will release the flush of water. When the armature 25 has entirely entered the said electromagnet, the arm 24 will close the circuit at the contacts 23, and thus the current will flow in 27, the electromagnet 15, the contact piece 23, and the terminal 28; the electromagnet 15 is thus energized, and the armature 17 will be brought against the terminal 19, thus opening the circuit of the flushing electromagnet, and the several parts will return to the inoperative position.

Figure 6 represents an opening device which may be mounted on a door which is to be opened from the interior of the latrines. The device must be mounted on the other side if the door opens in an opposite direction. In

the drawings, 29 is an insulated plate, which is to be mounted on the door 30. A reaction spring 31 is secured at one end to the said plate and at the other end to a handle 32 whose stem 33, limited by two stops 34 and 35 is slidable in an aperture 35 formed in the cover 37, which is secured to the plate 29. The spring strip with a contact piece 38 controlled by the end 39 of the reaction spring 31, and also the spring strip with a contact piece 40 are secured to the plate 29, these two strips being connected to the circuit of the flushing electromagnet.

The system shown in Figure 6 operates as follows:

When leaving the latrines, the person will push the knob 32 and its part 33 then slides in the aperture 36; the end 39 of the reaction spring pushes the spring strip 38, which will then come into contact with the strip 40. The circuit of the flushing electromagnet is closed thereby. As the person continues to push the door, the stop 34 will come into contact with the cover 37 and thus open the door. When the person has passed through the door, the parts will resume under the action of the spring 31 the position shown in Figure 8.

Figure 7 is a general view of a latrine and shows the door thereof, and means for operating the flushing device. In this figure the door of the latrine is designated by the letter *a*. A flushing device *b* is provided with a starting lever *c* which is connected with the movable armature *d* of an electro-magnet *e*. The electrical current passing through said magnet is supplied by a source of electrical energy *f*. A switch *g* actuated by the lock *h* of the door *a* is situated in the same electrical circuit. Due to this arrangement the electrical current passing through a magnet connected with the flushing device is operated by means of a switch forming a part of a door lock mechanism.

This invention is applicable to cocks as well as to tanks which are used for flushing purposes. It is further applicable to ordinary cocks, and to push-cocks. If an ordinary cock is employed with the electromagnetic arrangement, the duration of the opening of the cock may be prolonged by a time-retarded electric relay, or by clockwork, by which the flushing electromagnet will be energized for a longer time than that of the contact made by the contact devices of the door, the electric bolt, or the electric knob.

1. Means for automatically flushing the water in latrines when opening doors of same, comprising in combination a flushing device, an electromagnet, whose movable armature is positively connected with said flushing device, a switch electrically connected with said electromagnet, means for opening a latrine door and means for connecting said switch with said first-mentioned means.

2. Means for automatically flushing the water in latrines when opening doors of same, comprising in combination a flushing device, an electromagnet, whose movable armature is positively connected with said flushing device, a switch, spring strips carrying the two terminals of said switch, an insulating plate attached to one of said spring strips, a ramp attached to said plate, a lock bolt and a stud rigidly secured to said bolt, said stud being adapted to come into contact with said bolt and to put thereby said switch in circuit.

3. Means for automatically flushing water in latrines when opening doors of same, comprising in combination a flushing device, an electromagnet, whose movable armature is positively connected with said flushing device, two auxiliary electromagnets, a switch adapted to be actuated by said auxiliary electromagnets alternatively in two directions, another switch electrically connected with one of said auxiliary electromagnets, a lock bolt connected with the second mentioned switch, said switch being operated by locking of said bolt to actuate in one direction on the first-mentioned switch, another switch electrically connected with said auxiliary electromagnet and actuated when opening the door to switch on the first-mentioned electromagnet and thereby produce the flushing of water and a third switch connected with the second one of said auxiliary electromagnets and with the movable armature of the first-mentioned electromagnet, the last mentioned switch being operated by the first-mentioned electromagnet to actuate in an inverse sense the first-mentioned switch and to switch off thereby the first-mentioned electromagnet.

4. Means for automatically flushing the water in latrines when opening doors of same, comprising in combination a flushing device, an electromagnet, whose movable armature is positively connected with said flushing device, a switch electrically connected with said electromagnet, means for opening a latrine door and means for connecting said switch with said first-mentioned means with said electromagnet, spring strips carrying the two terminals of said switch, an insulating plate attached to the door and carrying said spring strips, a door knob, a stem, connected with said knob, a cover for said insulating plate and a spring maintaining said stem out of contact with the terminals of said switch, said stem connecting said terminals and creating an electrical current when said knob is operated to open the door.

In testimony whereof, I affix my signature.
